Primary Examiner — Richard Kearney*Assistant Examiner* — David Weir(74) *Attorney, Agent, or Firm* — Ricky Lam(57) **CLAIM**

The ornamental design for a wheelbarrow as shown and described.

DESCRIPTION

FIG. 1 is a front, top, and right perspective view of a wheelbarrow showing my new design.

FIG. 2 is a rear, bottom, and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion indicated with the number 9 in FIG. 1; and,

FIG. 10 is another front, top, and right perspective view showing the wheelbarrow in an alternate state of use.

The broken lines shown in the drawings represent portions of the wheelbarrow that form no part of the claimed design. The broken lines consisting of short and long dash lines encircling the enlarged detail views are for annotative purposes and form no part of the claimed design.
